(57) **CLAIM**

We claim the ornamental design for a solar carport, as shown and described.

DESCRIPTION

This application claims the benefit of priority to U.S. patent application Ser. No. 16/600,384, entitled Solar Carport and Water Management and Icicle Prevent System for Solar Carports and Canopies, and to U.S. patent application Ser. No. 16/600,403, entitled Solar Carport and Water Management for Solar Carports and Canopies, and to PCT application Serial No. PCT/US2019/055995, entitled Solar Carport and Water Management and Icicle Prevent System for Solar Carports and Canopies, and to PCT application Serial No. PCT/US2019/055998, entitled Solar Carport and Water Management for Solar Carports and Canopies, filed on even date.

FIG. 1 is a front perspective view of solar carport;
FIG. 2 is a front view of the solar carport depicted in FIG. 1;

FIG. 3 is a rear view of the solar carport depicted in FIG. 1;
FIG. 4 is a side view of the solar carport depicted in FIG. 1;
FIG. 5 is a side view of the solar carport depicted in FIG. 1;
FIG. 6 is a top view of the solar carport depicted in FIG. 1;
and,

FIG. 7 is a bottom view of the solar carport depicted in FIG. 1.

Dash lines are not claimed, and are included only to show details of the solar carport in the drawings.
